[57] CLAIM

The ornamental design for a compartmental cover for a container, as shown and described.

DESCRIPTION

FIG. 1 is a top front perspective view of a compartmental cover for a container showing our new design;

FIG. 2 is a front elevational view thereof;

FIG. 3 is a right side elevational view thereof, the left side being a mirror image of the right side;

FIG. 4 is a rear elevational view thereof;

FIG. 5 is a top plan view thereof; and,

FIG. 6 is a bottom plan view thereof.
